[57] CLAIM

The ornamental design for a electrical trunking, utility
box, as shown and described.

DESCRIPTION

FIG. 1 is a perspective view from above, front and one
side of the electrical trunking, utility box showing my
new design;

FIG. 2 is an elevational view of the opposite side
thereof;

FIG. 3 is a front elevational view thereof;

FIG. 4 is a rear elevational view thereof; and

FIG. 5 is a top plan view thereof.

*FIG. 1.**FIG. 2.**FIG. 3.**FIG. 4.**FIG. 5.*
